United States Patent Office

Des. 182,371
Patented Mar. 25, 1958

182,371

TOOTHPICK DISPENSER OR SIMILAR ARTICLE

Irving Mayer, San Antonio, Tex.

Application November 5, 1956, Serial No. 43,656

Term of patent 14 years

(Cl. D52—2)

Fig. 1.

Fig. 2.

Figure 1 is a perspective view of a toothpick dispenser or similar article, showing my new design.

Figure 2 is a rear elevational view.

The opposite side of the dispenser is plain.

I claim:

The ornamental design for a toothpick dispenser or similar article, as shown and described.
